George C. Lunt
INVENTOR

UNITED STATES PATENT OFFICE.

GEORGE C. LUNT, OF GREENFIELD, MASSACHUSETTS.

DESIGN FOR A SPOON, FORK, OR SIMILAR ARTICLE.

53,685.

Specification for Design.

Patented Aug. 5, 1919.

Application filed April 26, 1919. Serial No. 293,022. Term of patent 7 years.

To all whom it may concern:

Be it known that I, GEORGE C. LUNT, a citizen of the United States, residing at Greenfield, in the county of Franklin and State of Massachusetts, have invented a new, original, and ornamental Design for Spoons, Forks, or Similar Articles, of which the following is a specification.

Figure 1 is a front plan view.

Fig. 2 is a rear plan view.

Fig. 3 represents a sectional view on the line as indicated.

I claim:

The ornamental design for a spoon, fork, or similar article as shown.

In testimony whereof I affix my signature in presence of two witnesses.

GEORGE C. LUNT.

Witnesses:

HORATIO S. DU MONT,
GEO. H. DAVIS.
